UNITED STATES PATENT OFFICE

2,450,293

VALVE PULLER

Harold L. Oserowsky, Bay City, Mich.

Application June 7, 1945, Serial No. 598,036

1 Claim. (Cl. 29—283)

1

This invention relates to improvements in valve pullers and has as its principal object the provision of means for lifting a valve from a cylinder block in such manner that the pull is exerted in direct vertical alignment with the axis of the valve, so that any tendency to set up bending stresses in the valve or in the valve stem is eliminated.

Another object is to provide a valve puller that uniformly engages practically the entire under face of the valve, thereby distributing the pulling stresses over the entire area of the valve, avoiding bending stresses and chipping along the edges of the valve proper.

A further object is to design an adjustable valve puller which is readily adjustable to accommodate valves of various sizes and which can be quickly attached to and/or removed from the valve.

Still a further object is to provide a threaded stem equipped with a freely rotatable disk, said stem being adjustable to move the disk into and out of engagement with the face of the valve and to compensate for valves of various sizes and thicknesses.

With the above and other objects in view, the present invention consists in the combination and arrangement of parts, hereinafter more fully described, illustrated in the accompanying drawing, and more particularly pointed out in the appended claims, it being understood that changes may be made in the form, size, proportion and minor details of construction without departing from the spirit, or sacrificing any of the advantages of the invention.

In the drawing:

Fig. 1 is a side-elevational view of my improved valve lifter as applied to a valve, the engine block being shown in section.

Fig. 2 is a fragmentary side-elevational edge view, the broken lines indicating the range of adjustment.

Fig. 3 is a top plan view taken on the line 3—3 of Fig. 1.

Fig. 4 is a fragmentary, part-sectional view showing the rotatable disk fixed on the end of the adjustable stem.

The valves of internal combustion engines often become gummy, coated with carbon etc., and require considerable force and/or shock to effect their removal for grinding, replacement or for any other purpose, this pulling force must of necessity be in alignment with the vertical axis of the valve to avoid bending of the stem, and care must be exercised to avoid chipping the

edges of the valve, and I have therefore perfected a valve puller in which the pulling force is always in vertical alignment, and the edges of the valves protected, said puller being readily operable so that stuck valves can be readily and easily removed without damage to the valve proper or bending of the stem.

Referring now more particularly to the drawing in which I have shown the preferred embodiment 10 of my invention; the numeral 5 indicates the motor block of a conventional internal combustion engine provided with a valve seat 6 as usual, and a valve 7 is mounted therein in the conventional manner.

15 The valve puller includes a gripping member "G" comprising vertically spaced disk sections 8 and 9 respectively connected by the vertically disposed web 10 as clearly shown in Fig. 1 of the drawing, this web extending partially around the 20 outer circumference of the disk sections, with the open section 11 forming a passage to accommodate the head of the valve 7, the lower disk section 9 being formed with a slotted opening 12 which accommodates the stem 13 of the valve and 25 permits ready positioning of the valve in the gripping member, the edges of the slotted passage being beveled as at 14 to eliminate chipping or marring of the valve head.

A hub 15 is formed integral with the upper disk 30 section 8 of the gripping member "G," and is centrally bored and threaded as at 16 to accommodate the lower threaded end of the stem 17, an intermediate disk 18 being revolvably mounted on the lower end of the stem by means of the 35 shouldered screw 19.

A knurled head 20 is provided on the upper end of the stem 17, and a striker member 21 is slidably mounted on said stem, the ends 22 being beveled as shown, the upper end engaging the head 20 to impart a sharp hammer blow when 40 the tool is operated.

The striker member 21 is slidably mounted on the stem 17 and is relatively heavy, the end sections 22 being tapered and reduced to eliminate 45 the possibility of pinching, and this striker member, in practice, is forced upwardly against the head 20 to form a sharp impact or hammer blow when the tool is in use.

In operation, the gripping member "G" is first 50 moved over the head "V" of the valve, the valve stem 13 being accommodated in the slot 12, and when the valve is in centered position, the operator grasps and rotates the knurled head 20 to thread the stem downwardly through the disk section 8 until the intermediate disk 18 is in inti-

mate contact with the head of the valve, after which the operator grasps the striker 21, forcing it upwardly against the head 20 to produce a sharp shock or hammer blow, and one or more of said shocks usually frees and lifts the valve, whereupon the freed valve is disengaged from the gripping member, and the tool is then ready for use on the next valve.

The device can be utilized for removing truck or tractor valves or other valves of larger size, as the intermediate disk 18 has a considerable range of vertical adjustment, but the removing operation is identical with that above described.

The gripping member "G" can be made in any desired manner, it can be formed of two individual disks connected by studs, pins or other means (not shown), but I find that forming it in one integral unit as shown in the instant application is very satisfactory.

From the foregoing description, it will be obvious that I have perfected a very simple, practical, and inexpensive valve removing tool for removing valves from engines.

What I claim is:

In a valve puller comprising spaced-apart connected disks forming a valve head accommodat-

ing chamber therebetween, a valve head opening in the outer periphery thereof, a centrally disposed threaded opening in the upper disk, a vertical stem threaded therein, and extending into said chamber, a relatively thin, intermediate disk connected to the end of the stem within said chamber, said disk being vertically adjustable as the stem is rotated to accommodate valve heads of various sizes in the chamber between the lower disk and the intermediate disk.

10 HAROLD L. OSEROWSKY.
